CLAIM

We claim the ornamental designs for pockets, as shown and described.

DESCRIPTION

FIG. 1 is a top perspective view of a first embodiment of a pocket embodying our new design, the pocket in a closed configuration having a flap held closed with a hook and loop closure mechanism, and a region of adhesive that is covered with a piece of liner on the pocket's bottom surface.

FIG. 2 is a top perspective view of the pocket of FIG. 1 with the flap in a partially open configuration.

FIG. 3 is a top perspective view of the pocket of FIG. 1 with the flap in an open configuration.

FIG. 4 is a bottom perspective view of the pocket of FIG. 1.

FIG. 5 is a bottom perspective view of the pocket of FIG. 1 with the piece of liner partially removed from the region of adhesive.

FIG. 6 is a top plan view of the pocket of FIG. 1.

FIG. 7 is a bottom plan view of the pocket of FIG. 1.

FIG. 8 is a front-edge elevational view of the pocket of FIG. 1.

FIG. 9 is a back-edge elevational view of the pocket of FIG. 1.

FIG. 10 is a left-side elevational view of the pocket of FIG. 1.

FIG. 11 is a right-side elevational view of the pocket of FIG. 1.

FIG. 12 is a top perspective view of a second embodiment of a pocket embodying our new design, the pocket in a closed configuration having a flap held closed with a hook and loop closure mechanism, and a region of adhesive that is covered with a piece of liner on the pocket's bottom surface.

FIG. 13 is a top perspective view of the pocket of FIG. 12 with the flap in a partially open configuration.

FIG. 14 is a top perspective view of the pocket of FIG. 12 with the flap in an open configuration.

FIG. 15 is a bottom perspective view of the pocket of FIG. 12.

FIG. 16 is a bottom perspective view of the pocket of FIG. 12 with the piece of liner partially removed from the region of adhesive.

FIG. 17 is a top plan view of the pocket of FIG. 12.

FIG. 18 is a bottom plan view of the pocket of FIG. 12.

FIG. 19 is a front-edge elevational view of the pocket of FIG. 12.

FIG. 20 is a back-edge elevational view of the pocket of FIG. 12.

FIG. 21 is a left-side elevational view of the pocket of FIG. 12.

FIG. 22 is a right-side elevational view of the pocket of FIG. 12.

FIG. 23 is a top perspective view of a third embodiment of a pocket embodying our new design, the pocket in a closed configuration having a flap held closed with two hook and loop closure mechanisms, and a region of adhesive that is covered with a piece of liner on the pocket's bottom surface.

FIG. 24 is a top perspective view of the pocket of FIG. 23 with the flap in a partially open configuration.

FIG. 25 is a top perspective view of the pocket of FIG. 23 with the flap in an open configuration.

FIG. 26 is a bottom perspective view of the pocket of FIG. 23.

FIG. 27 is a bottom perspective view of the pocket of FIG. 23 with the piece of liner partially removed from the region of adhesive.

FIG. 28 is a top plan view of the pocket of FIG. 23.

FIG. 29 is a bottom plan view of the pocket of FIG. 23.

FIG. 30 is a front-edge elevational view of the pocket of FIG. 23.

FIG. 31 is a back-edge elevational view of the pocket of FIG. 23.

FIG. 32 is a left-side elevational view of the pocket of FIG. 23; and,

FIG. 33 is a right-side elevational view of the pocket of FIG. 23.
